C. W. METZGAR.
FLUID COMPRESSOR.
APPLICATION FILED AUG. 3, 1921.

1,430,577.

Patented Oct. 3, 1922.

UNITED STATES PATENT OFFICE.

CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY.

FLUID COMPRESSOR.

Application filed August 3, 1921. Serial No. 489,625.

To all whom it may concern:

Be it known that I, CHESTER W. METZGAR, a citizen of the United States, and a resident of Easton, county of Northampton, 5 and State of Pennsylvania, have invented a certain Fluid Compressor, of which the following is a specification, accompanied by drawings.

This invention relates to compressors, but 10 more particularly to a compressor for compressing gas with varying discharge pressures.

In pumping gas, for instance, from a gas bell supplied from any suitable source, for 15 use at a remote point, as in a city supply, the condition arises in which the compressors shall continue to operate for a short time, without however, pumping gas from the gas bell. Otherwise continuous pumping 20 would drain down the gas in the bell to an undesirable point.

A regulator of the type disclosed in my copending application, Serial No. 489,626, filed August 3, 1921, has been selected to illustrate the invention, which regulator will 25 unload the compressor step by step according to successive changes in a predetermined line pressure and will completely unload the compressor at this pressure as usual 30 with this type of regulator. The object of the present invention is to enable the compressor to be completely unloaded when the line pressure falls below the predetermined pressure, at which the regulator has heretofore unloaded the compressor.

The clearance pockets, designed for unloading at a predetermined pressure, would 40 not have sufficient volume to completely unload the compressor at a pressure lower than the predetermined pressure, and my invention in its preferred form enables the conditions to be met with the same clearance pockets by by-passing the fluid from one pocket to another, when all the clearance 45 valves are open, so that the gas is by-passed from one end of the cylinder to the other.

My invention avoids the use of hand starting unloaders, because the compressor may 50 be started against the pressure in the discharge line, and the gas will be circulated back and forth through the clearance pockets and by-pass from one end of the compressor to the other, until the by-pass is closed automatically by the regulator.

The invention is shown in one of its preferred forms in the accompanying drawings, in which—

Figure 1 is a diagrammatic view partly in longitudinal section of portions of a compressor embodying the invention, and

Figure 2 is an enlarged detail longitudinal sectional view of one of the by-pass valves.

Referring to the drawings, the compressor may be of any suitable type, but I have chosen for illustrative purposes to show a duplex low pressure compressor having a low pressure cylinder A and double acting piston B, and another low pressure cylinder C and double acting piston D. The pistons, having the piston rods E and F may be driven from any suitable source or sources of power (not shown) and the cylinders are provided respectively with clearance pockets G and H, and J and K communicating with the cylinders and controlled by suitable clearance valves T contained in the valve casings 1, 2, 3 and 4 respectively mounted on the heads O and P of the cylinder A and similar valves T in similar valve casings 1, 2, 3 and 4, mounted on the air heads Q and R of the cylinder B. The compressor valves S for the cylinder A and the valves U for the cylinder B, which may be of the plate type, are mounted in the air heads and serve as inlet or discharge valves in the usual manner. The compressor cylinders are assumed to be connected by suitable piping to each other and to the main receiver V, the piping not being shown for the sake of simplicity.

The chambers W in the air heads, in which the clearance valves T operate, communicate with the various clearance pockets G, H, J and K in the cylinders A and C by means of the ports X, and the pockets are provided with by-pass ports Y so that adjacent pockets may be connected by by-pass connections in the form of casings Z, controlled by by-pass valves a operating in by-pass casings 4^a.

The clearance valves T and by-pass valves a may all be preferably of the construction shown in detail in Figure 2, in which the valve seat b is provided with a guide c over which the hollow head d of a valve T or a slides, and upon which the valve is guided. A spring e, compressed between the guide c

and the valve head *d*, tends to open the valve when line pressure from the receiver *V*, which tends to close the valve, is relieved. A pin *f* passing through a stuffing box *g* 5 bears against the valve head *d* and against the piston *h*, operating in the piston chamber *j*. Receiver pressure is supplied to the chamber *j* behind the piston *h* through a suitable pipe connection *4^a*. The by-pass 10 valves *a* are provided with manual means for rendering the valves inoperative, by holding them closed and for this purpose the valve casings *4^a* are provided with adjustable set screws *k* in the casing heads *o*. 15 The set screws may be provided with squared ends *p* and lock nuts *q* and when a set screw is screwed in a sufficient distance, the piston *h* will be forced inwardly and the by-pass valve will be maintained closed. 20 The clearance valves *T* and the by-pass valves *a* are all adapted to be maintained in closed position by receiver pressure from the receiver *V*, and the valve casings are all connected by suitable pipe connections to the 25 valve chest *r* of a regulator *s*, of the type described in my co-pending application, Serial No. 489,626, filed August 3, 1921. This regulator operates in substantially the same manner as the regulator disclosed in 30 United States Patents Nos. 1,027,757; 1,027,758 and 1,027,760 granted May 28, 1912, to William Prellwitz, assignor to Ingersoll-Rand Company. In such a regulator, the movements of a plurality of main regulator 35 valves within the valve chest *r* for controlling the loading and unloading of the compressor, are in turn controlled by an auxiliary regulator valve within the valve chest *r*. With such a regulator, clearance pockets of 40 the compressor are brought into and out of communication with the interior of the compressor cylinders, for securing a step by step unloading or loading of the compressor as the fluid in the main receiver tank *V* 45 reaches successively attained pressures.

Without describing the internal construction of the regulator *s*, it will be sufficient for the purposes of this invention to describe the mode of operation. The valve casings 1, 50 2, 3 and 4 of the cylinder *A* are connected to the similarly numbered valve casings 1, 2, 3 and 4 of the cylinder *B* by means of the pipes *1^b*, *2^b*, *3^b* and *4^b*, which are in turn connected by branch pipes *1^c*, *2^c*, *3^c*, and *4^c*, 55 to the valve chest *r* of the regulator *s*, so that the clearance valves *T* are operated in pairs. The valve casings *4^a* of the by-pass valve *a* are all connected by branch pipes *4^c* to the pipes *4^b*, which connect the valve casings *4^a* of the pairs of clearance valves *T* so that when the last pair of clearance 60 valves *T* is opened in the successive step by step operation of unloading by relieving the pressure behind the heads of said clearance valves *T*, all the by-pass valves *a* are also

opened in order to open the by-pass connections between the adjacent clearance pockets *G* and *H* and *J* and *K*. In this last successive step of unloading, the compressor will be completely unloaded because the 70 fluid will be pumped back and forth from one end of a cylinder to the other through adjacent clearance pockets, which are in communication through the open by-pass connections. 75

The valve chest *r* of the regulator *s* is connected by a pipe *t* to the pipe *u*, which connects the receiver tank *V* with the casing *v* of a fluid actuated device, having a lever arm *w* adapted to be connected by means of 80 a rod *x* to the auxiliary controlling valve of the regulator *s*. The lever *w* is pivoted at *y* on the frame *v*, and the weight of the lever is carried on a pin *z* movable in any suitable manner in accordance with successively attained receiver pressures. The end of the lever *w* may be weighted by the weights *2^c* and a rod *3^e* pivoted at *4^e* to the lever *w* extends through the frame of the device and is provided with a cap *5*, between which and the frame, the spring *5^a* is compressed for resisting upward movements of the lever. A stop *6* on the rod *3^e* limits the downward movement of the lever. Fluid pressure is exhausted from the valve chest *r* through 95 the exhaust pipe *7* communicating with the bottom of the valve chest and the exhaust pipe *8* communicating with the top of the valve chest through the frame *v* of the controlling device. In the position of the parts 100 indicated in Figure 1, the controlling lever *w* has been raised by fluid pressure in the receiver tank *V* to its uppermost position, in which case pressure has been relieved from behind the heads or pistons *h* of all the 105 clearance valves *T* and by-pass valves *a* so that all of said valves have been successively automatically opened and the compressor is completely unloaded. The provision of the by-pass valves *a* avoids the necessity of 110 opening and closing hand unloader valves and a valve on the discharge line when the compressor is started up against the pressure in the discharge line. In accordance with my construction, the compressor is unloaded on starting, due to the open by-pass connections *Z* between adjacent clearance 115 pockets, after which the by-pass valves *a* will be automatically closed as the compressor builds up pressure, to close connection 120 between adjacent pockets, by closing the by-pass valves.

I claim:

1. A fluid compressor comprising a cylinder and piston, clearance pockets formed in 125 the walls of the cylinder adapted to communicate with each end of the cylinder, fluid actuated clearance valves controlling communication between the cylinder and said pockets, and fluid actuated means for con- 130

trolling two adjacent pockets for completely unloading the compressor.

2. A fluid compressor comprising a cylinder and piston, clearance pockets adapted to communicate with each end of the cylinder, fluid actuated clearance valves controlling communication between the cylinder and said pockets, a by-pass connecting adjacent pockets, and a fluid actuated valve controlling said by-pass connection.

3. A fluid compressor, comprising a cylinder and piston, clearance pockets formed in the walls of the cylinder adapted to communicate with each end of the cylinder, fluid actuated clearance valves controlling communication between the cylinder and said pockets, and fluid actuated means for connecting two adjacent pockets at a predetermined line pressure for completely unloading the compressor.

4. A fluid compressor comprising a cylinder and piston, clearance pockets adapted to communicate with each end of the cylinder, fluid actuated clearance valves controlling communication between the cylinder and said pockets, a by-pass connecting adjacent pockets, and a fluid actuated valve automatically controlling said by-pass connection.

5. A fluid compressor comprising a cylinder and piston, clearance pockets adapted to communicate with each end of the cylinder, clearance valves controlling said pockets, means for automatically connecting two pockets at a predetermined line pressure, and manual means for rendering said automatic means inoperative.

6. A fluid compressor comprising a cylin-

der and piston, clearance pockets adapted to communicate with each end of the cylinder, fluid actuated clearance valves controlling communication between the cylinder and said pockets, fluid actuated means for connecting two adjacent pockets at a predetermined line pressure for completely unloading the compressor, and manual means for rendering said fluid actuated means inoperative.

7. A fluid compressor comprising a cylinder and piston, clearance pockets adapted to communicate with each end of the cylinder, fluid actuated clearance valves controlling communication between the cylinder and said pockets, a by-pass connecting adjacent pockets, a fluid actuated valve automatically controlling said by-pass connection, and manual means for closing and maintaining said by-pass valve closed.

8. A fluid compressor comprising a cylinder and piston, clearance pockets adapted to communicate with each end of the cylinder, fluid actuated clearance valves controlling communication between the cylinder and said pockets and adapted to be actuated in succession as the line pressure reaches successively attained pressure, a by-pass connecting adjacent pockets, and a fluid pressure valve controlling said by-pass connection and adapted to be actuated substantially simultaneously with the movement of that clearance valve of the compressor last in order to be actuated.

In testimony whereof I have signed this specification,

CHESTER W. METZGAR.
